UNITED STATES PATENT OFFICE

PASQUALE GALASSI, OF NEW YORK, N. Y.

STRIP FOR FLOORS OF THE TERRAZZO TYPE

Application filed August 3, 1929. Serial No. 383,249.

This invention relates to improvements in the construction of terrazzo and similar floors, and more particularly refers to a new type of dividing strip adapted for use in connection with such floors.

Terrazzo, granolithic, stucco and similar floors usually comprise a lower or foundation bed made of concrete or cement or mortar or other suitable material, and an upper or 10 finishing layer generally consisting of a mixture of marble chips and cement, by means of which a good durable surface may be obtained as well as pleasing designs and color effects of a practically unlimited variety.

The upper layer which is generally placed in position after the foundation layer has been allowed to harden to a sufficient degree of consistency, is generally divided into a 20 number of panels or units in a predetermined arrangement, which are obtained by outlining the desired design by means of dividing strips placed on or through the foundation layer.

25 These strips generally consist of flat metal bars set on edge having their upper edges flush with the surface of the floor; and said bars are generally provided with anchoring and positioning means insuring a firm binding action between the strips and the materials of which the floor is composed.

These bars are generally made of relatively soft metal such as brass for instance, the wearing qualities of which are approximately equal to those of the floor itself; and according to the nature of the floor and of the design to be produced, the dividing strips may be of various thicknesses and lengths.

40 Relatively thin strips may readily be obtained out of sheet metal, and are suitable for floors of moderate size; however relatively large floors, or floors composed of relatively large units, call for strips having sufficient rigidity to withstand the lateral pressure of the material, without bulging when the floor is laid. These heavier strips are also generally made out of sheet metal but brass being expensive material, their use materially increases the cost of the floor.

45 The primary object of this invention is

to provide dividing strips of a novel and improved construction in which only a relatively thin section made of metal showing through the floor is used together with another section made of less expensive material 55 completing the strip, said two sections having portions overlapping each other, so as to jointly impart to the strip the necessary rigidity.

Another object is to provide a dividing strip of the character specified in which the two sections are joined to each other purely by means of punching press operations avoiding the necessity of using riveting or welding or other relatively expensive processes.

60 Other objects and advantages of the present invention will more fully appear as the description proceeds and will be set forth and claimed in the appended claims.

Various embodiments of my invention are 70 illustrated in the accompanying drawings, in which:

Fig. 1 is a fragmentary view in perspective of a strip composed of two flat sections, the inner edges of which overlap and are 75 joined to each other;

Fig. 2 is a fragmentary longitudinal section thereof;

Fig. 3 is a fragmentary view in perspective of another strip also embodying my invention in which the inner edges of the two sections are bent laterally to form a reinforcing flange;

Fig. 4 is a fragmentary view in perspective of a strip somewhat similar to that shown 85 in Figs. 1 and 2, in which the joining and anchoring means can also be used as positioning means; and

Fig. 5 is a vertical cross section showing the strip illustrated in Fig. 4 in position.

90 In another patent application entitled Bimetallic floor strip, Serial No. 375,053, I have shown and described dividing strips made of two sections having their inner edges overlapping each other and secured to each other 95 by means of rivets.

In another application entitled Composite floor dividing strips, Serial No. 376,808. I have also described and claimed dividing strips of the same character in which how- 100

ever, the two sections are joined to each other by means of welding or brazing or similar operations.

The methods of construction advocated in the said two applications are to be recommended when a relatively heavy upper section is to be joined with a lighter or thinner lower section. When both sections are made of relatively thin light gauge materials however, it is possible to adopt other methods of joining the sections to each other, which are more economical and to a certain extent more reliable than the riveting or welding or brazing operations above mentioned.

I have found in practice that a positive joining of the two sections of the strip may be effected by partially punching and forcing out laterally burrs or lugs from the two adjoining thicknesses of metal. In this manner, the two sections composing the strip remain securely joined to each other by virtue of the friction mutually exerted between the two metal tongues or extensions formed at each point of junction, said extensions at the same time forming prongs or other laterally projecting members which effectively serve as anchoring means for the strip.

Such a method of joining two sections of a strip has been shown by me in a patent entitled Floor laying devices, Patent No. 1,667,813 granted to me April 24, 1928; the construction of strip described in said patent however, was essentially different from that of the strips forming the subject of the present application.

The strip represented in Figs. 1 and 2 comprises an upper section 10 and a lower section 11, both said sections being made of relatively light gauge metal and having their inner edges overlapping each other so as to form an intermediate thicker portion 12 of the strip.

As a general rule the upper section will be made of brass while the lower section may be made of steel, this being a less expensive yet stronger and stiffer material. As shown in the drawing, the two sections are joined to each other by partially punching and forcing out laterally burrs or lugs from the two adjoining thicknesses of metal at spaced intervals forming prong members 13, 14, etc., laterally projecting from the intermediate portion of the strip.

These prongs may all be bent to one side or else they may be bent in alternate directions as shown. By virtue of this construction the two sections of which the strip is composed are permanently and securely connected to each other to form a single unit adapted to be conveniently handled and placed in position with a minimum expenditure of time and labor.

At the same time the laterally extending prongs 13, 14 provide very effective anchoring means for the strip units becoming em-

bedded in the concrete or other material of which the bed is composed, when said material is still in its plastic condition.

A strip of greater rigidity will be obtained if the inner edges of the two sections are bent laterally of the body of said sections so as to form horizontal flanges therefor. A strip of this character is illustrated in Fig. 3 where the upper section 15 and the lower section 16 have their inner edge portions bent at one side to form laterally extending flanges 17, 18, said two flanges abutting against each other and forming a means for connecting the sections of the strip together by forcing out from said flanges downwardly directed prongs 19 at spaced intervals, as shown.

In a strip of this character, the prongs still act as anchoring means for the strip while the flange formed by flanges 18, 18 forms a positive positioning means for the strip providing a surface which may rest directly on top of the lower layer of the floor and which will be covered by the upper layer.

Such a flange insures the vertical alignment of the strip and also materially increases its rigidity so that materials of very light gauge may be used.

In Fig. 4 I illustrate another strip composed of an upper section 20 and a lower section 21 the inner edge portions of which overlap to form an intermediate thicker portion 22 of the strip. In this case the two sections are joined together by forcing out laterally at spaced intervals open top cup members 23 which are struck off the two overlapping thicknesses of metal.

These cup members also provide anchoring and positioning means and furthermore tend to strengthen rather than weaken the section of the strip, at the same time increasing its rigidity.

A strip of this character is shown in Fig. 5 where 24 designates the lower layer or bed of a terrazzo floor resting on top of the foundation bed 25. The lower portion of the strip is embedded into the lower layer 24, its lower edge resting against the top of the foundation bed and the upper edges of the open top cup members defining the depth of the lower layer 24.

The floor is completed by an upper layer 26 within which is embedded the upper portion of the strip, the upper edge 27 of said strip being level with the surface of the floor.

From the foregoing it will be seen that I provide a construction of strip which is more economical than those described and claimed in my other two pending applications above referred to and which is particularly suitable for use when light gauge sections are employed.

The inventive idea may be applied in strips the construction of which may be different from those shown; the drawings will there-

fore be understood as being intended for illustrative purposes only and not in a limiting sense. Accordingly, I reserve the right to carry my invention into practice in all those ways and manners, which may enter, fairly, into the scope of the appended claims.

I claim:

1. A floor strip of the character described, comprising an upper section and a lower section, each section having the inner portion of one of its surfaces only abutting against a corresponding portion of one of the surfaces of the other section, and members simultaneously struck off both sections and offset laterally thereof, said members permanently connecting said two sections to each other, and forming anchoring means therefor.

2. A floor strip of the character described, comprising an upper section and a lower section, each section having the inner portion of one of its surfaces only abutting against a corresponding portion of one of the surfaces of the other section, and a plurality of open top cup members simultaneously struck off both sections and offset laterally thereof, said members permanently connecting said two sections to each other, and forming anchoring means therefor.

3. A floor strip of the character described, comprising an upper section and a lower section, each section having the inner portion of one of its surfaces only abutting against a corresponding portion of one of the surfaces of the other section, and a plurality of spaced open top cup members simultaneously struck off both sections and offset laterally thereof, alternately at one side and then at the other, said members permanently connecting said two sections to each other, and forming anchoring means therefor.

4. A floor strip of the character described, comprising an upper section and a lower section, each section having the inner portion of one of its surfaces only abutting against a corresponding portion of one of the surfaces of the other section, and a plurality of open top cup members simultaneously struck off both sections and offset laterally thereof, said members permanently connecting said two sections to each other, and forming anchoring means therefor, the upper edges of said cup members being at a distance from the upper edge of said strip, corresponding to the thickness of the upper layer of the floor into which said strip is to be embedded.

5. A floor strip of the character described, comprising an upper section and a lower section, each section having the inner portion of one of its surfaces only abutting against a corresponding portion of one of the surfaces of the other section, and a plurality of spaced open top cup members simultaneously struck off both sections and offset laterally thereof, alternately at one side and then at the other, said members permanently connecting said

two sections to each other, and forming anchoring and positioning means therefor.

6. A floor strip of the character described, comprising an upper section and a lower section, each section having the inner portion of one of its surfaces only abutting against a corresponding portion of one of the surfaces of the other section, and a plurality of open top cup members simultaneously struck off both sections and offset laterally thereof, said members permanently connecting said two sections to each other, and forming anchoring means therefor, said two sections being made of different metals.

7. A floor strip of the character described, comprising an upper section and a lower section, each section having the inner portion of one of its surfaces only abutting against a corresponding portion of one of the surfaces of the other section, and a plurality of spaced open top cup members simultaneously struck off both sections and offset laterally thereof, alternately at one side and then at the other, said members permanently connecting said two sections to each other, and forming anchoring and positioning means therefor, said two sections being made of different metals.
